UNITED STATES PATENT OFFICE

ROBERT H. RUSSELL, OF WORCESTER, MASSACHUSETTS, ASSIGNOR TO ROCKWOOD SPRINKLER COMPANY OF MASSACHUSETTS, A CORPORATION OF MASSACHUSETTS

FUSIBLE LINK

Application filed May 9, 1930. Serial No. 451,160.

This invention relates to a fusible link designed for use in connection with sprinklers, fire doors and other heat-controlled structures. My invention possesses particular advantages when used in sprinkler heads as will be hereinafter pointed out.

It is the general object of my invention to provide a fusible link of an improved construction so designed that it will be more quickly responsive to a rise in temperature.

A further object is to provide a fusible link in which the fusible metal is so disposed that accidental release of the sprinkler controlled thereby is rendered substantially impossible.

My invention further relates to arrangements and combinations of parts which will be hereinafter described and more particularly pointed out in the appended claims.

A preferred form of the invention is shown in the drawings, in which

Fig. 1 is a side elevation of a sprinkler head having my improved fusible link mounted thereon;

Fig. 2 is a side elevation of the fusible link, looking in the direction of the arrow 2 in Fig. 1;

Figs. 3, 4 and 5 are perspective views of the different parts comprising my improved link;

Fig. 6 is a sectional elevation of the fusible link; and

Fig. 7 is a sectional bottom view, taken along the line 7—7 in Fig. 6.

Referring to the drawings, I have shown a sprinkler head of a commercial form which comprises a threaded support 10 having an open frame structure 11 projecting upwardly therefrom. A cap 12 closes the opening through the support 10 and the cap 12 is held firmly seated by locking levers 13 pressed downward by an adjusting screw 14. The outer ends of the levers 13 are provided with hooklike projections 15 which are normally held from separation by a fusible link to be described.

My improved fusible link comprises tension members 20 and 21 and a locking or retaining member 22. Each tension member is provided with an opening 23, preferably reinforced by a grommet 24, these openings be-

ing adapted to receive the hook-shaped ends of the levers 13.

The tension member 20 is provided with a rectangular opening 25 and the member 21 is provided with a corresponding opening 26. The openings 25 and 26 are positioned in alignment when the link is assembled.

The tension member 21 is also provided with a laterally projecting hood 30 comprising a flat top portion 31 and triangular side portions or braces 32. The projection 30 is also preferably provided with a recessed end portion 34. The locking member 22 is provided with an end projection 36 and with offset lugs or projections 37 at the opposite end of said member.

When the parts are assembled, as indicated in Fig. 6, the locking member 22 is disposed within and beneath the projecting hood 30, with the end projection 36 extending through the openings 25 and 26 in the tension members 20 and 21. The offset lugs 37 are disposed adjacent the recessed end portion 34 of the hood 30 but are of such height that the locking member cannot enter within the recessed portion 34.

After the parts are thus assembled, the adjacent faces of the tension members 20 and 21 are soldered or sweated together with a low melting solder and this solder is also disposed between the locking member 22 and the hood 30 and also within and around the recessed end 34 of the hood 30 and the offset lugs 37 of the locking member 22. Solder is also disposed in the openings 25 and 26 around the end 36 of the locking member 22.

It will be seen that the solder around the recessed end 34 and the outer end of the locking member 22 and its lugs 37 is so disposed that the solder is in "shear" and will strongly resist the swinging movement of the locking member 22 necessary to release the tension member 20 from the tension member 21. This disposal of the solder in shear, together with the long leverage at which the solder acts on the locking member, forms a very secure means for holding the locking member in position until a rise in temperature which will definitely soften or melt the solder.

The opening 26 in the member 21 is con-

tinued into the top surface of the hood 30, as indicated at 40, so that the locking member may be free to swing when the solder melts and the locking member is released.

5. When my improved fusible link is in use, the hood 30 and locking member 22 project into an opening between the locking levers 13, as indicated in Fig. 1, and are thus effectively protected from accidental damage.
10. Furthermore, when a fire occurs beneath a sprinkler equipped with my link, the hood 30, which is disposed in the path of the upwardly moving hot gases, "banks" them so that the retaining solder is more quickly melted.

Another advantage of the hood is that it acts as an "umbrella" to protect the fusible solder from gathering dirt or dust which might tend to insulate it and so retard its melting.

Having thus described my invention and the advantages thereof, I do not wish to be limited to the details herein disclosed, otherwise than as set forth in the claims, but what

25. I claim is:—

30. 1. A fusible link comprising two adjacent tension members and a locking member, one of said tension members having a hood projecting laterally therefrom, and said locking member being disposed within and beneath said hood and being secured in locking position by low-melting fusible material connecting a portion of said locking member to said hood.

35. 2. A fusible link comprising two adjacent tension members and a locking member, said tension members having aligned openings through which a portion of said locking member extends, and one of said tension members having a laterally projecting portion to and beneath which said locking member is secured by a portion of low-melting fusible material.

45. 3. A fusible link comprising two adjacent tension members and a locking member, said tension members having aligned openings, and one of said tension members having a hood projecting laterally therefrom, to and beneath which said locking member is secured by low-melting fusible material connecting a portion of said locking member to said hood, with one end of said locking member extending through said aligned openings.

55. 4. A fusible link comprising two adjacent tension members and a locking member, said tension members having aligned openings, and one of said tension members having a hood projecting laterally therefrom, to and beneath which said locking member is secured by low-melting material in shear, with one end of said locking member extending through said aligned openings.

65. 5. The combination in a fusible link as set forth in claim 4, in which the projecting

hood has its outer end recessed to receive a portion of said low-melting material.

6. The combination in a fusible link as set forth in claim 4, in which the projecting hood has its outer end recessed to receive a portion of said low-melting material, and in which means is provided to exclude the end of said locking member from the recessed end of said hood.

7. The combination in a fusible link as set forth in claim 4, in which the projecting hood has its outer end recessed to receive a portion of said low-melting material, and in which said locking member is provided with offset projections of such length as to engage the recessed end of said hood and thereby exclude the end of said locking member from said recessed end.

In testimony whereof I have hereunto affixed my signature.

ROBERT H. RUSSELL.
